CLAIM

(57) The ornamental design for an expanding alligator, as shown and described.

DESCRIPTION

FIG. 1 flat unfolded view of an ornamental design for an expanding alligator;

FIG. 2 is an assembled top plan expanded view thereof;

FIG. 3 is an assembled side expanded view thereof;

FIG. 4 is an assembled bottom expanded view thereof;

FIG. 5 is an assembled front view thereof;

FIG. 6 is an assembled rear view thereof;

FIG. 7 is an assembled top plan view thereof, shown in an alternative position;

FIG. 8 is an assembled side view thereof; and,

FIG. 9 is an assembled bottom view thereof.

The broken lines in FIG. 1 are fold lines which appear as solid lines in other figures when assembled.
